DESIGN FOR A SWEATER

Moses Langer, New York, N. Y.

Application December 24, 1936, Serial No. 66,724

Term of patent 7 years

To all whom it may concern:

Be it known that I, Moses Langer, a citizen of the United States, residing at New York city, in the county and State of New York, have invented a new, original, and ornamental Design for a Sweater, of which the following is a specification; reference being had to the accompanying drawing, forming a part thereof.

The figure is a front view of a sweater, showing my new design.

The back of the sweater is plain and unornamented. The characteristic feature resides in

the knitted letters which are formed in the process of knitting the garment and presenting surface ornamentation, with the horizontal and substantially horizontal strokes of the letters or characters raised above the surface of the background and the vertical and substantially vertical strokes of said letters or characters depressed below the surface of the background.

I claim:

The ornamental design for a sweater, as shown, and described.

MOSES LANGER.
